BABY PANTY

Barton R. Biever, Schuylkill Haven, Pa., assignor to Alpha Mills Corporation, Schuylkill Haven, Pa., a corporation of Pennsylvania

Application March 14, 1956, Serial No. 571,413

1 Claim. (Cl. 128—288)

This invention relates to baby panties.

Many garments for babies and small children have heretofore been proposed having an outer bifurcated garment with a waterproof lining but none of these has proven wholly satisfactory.

It is the principal object of the present invention to provide baby panties comprising an outer garment of textile fabric and an inner waterproof lining and in which the inner and outer components are combined in an improved manner.

It is a further object of the present invention to provide baby panties having an improved crotch construction.

It is a further object of the present invention to provide baby panties having inner and outer components, the outer component being made of flexible relatively inelastic material, and of a predetermined size, and the inner garment having expandible leg openings to accommodate the leg of the child using the garment.

It is a further object of the present invention to provide baby panties suitable for training use which are of attractive appearance and with which a suitable measure of protection is available.

Other objects and advantageous features of the invention will be apparent from the description and claims.

The nature and characteristic features of the invention will be more readily understood from the following description, taken in connection with the accompanying drawings forming part thereof in which:

Figure 1 is a front elevational view of baby panties in accordance with the present invention, parts being broken away in order to show the details of construction;

Fig. 2 is a top plan view of the garment shown in Fig. 1;

Fig. 3 is a fragmentary front elevational view showing the crotch of the panty in partly opened condition; and

Fig. 4 is a fragmentary sectional view taken approximately on the line 4—4 of Fig. 1.

It should, of course, be understood that the description and drawings herein are illustrative merely, and that various modifications and changes can be made in the structure disclosed without departing from the spirit of the invention.

Like numerals refer to like parts throughout the several views.

The baby panty, in accordance with the present invention, preferably include an outer bifurcated garment portion 10 and an inner bifurcated garment portion 11, suitably united as hereinafter explained.

The outer garment portion 10 can be of any desired flexible relatively inelastic material and is preferably of washable textile fabric, woven or knitted, as desired, one suitable material being corduroy.

The inner garment portion 11 can be made of any desired flexible but not necessarily elastic sheet or web material, preferably waterproof, and for this purpose sheet rubber, natural or synthetic, synthetic plastic sheet material or resin impregnated textile fabric, of suitable strength, is preferably employed.

The outer garment portion 10 preferably includes a

2

pair of similar front panel sections 13 and 14 connected along a front central vertical line of stitches at 15. A front waist band portion 16 extends along the top of the front panel sections 13 and 14 and is secured thereto along a line of stitches at 17.

One of the front panel sections, such as the panel section 13 may have a simulated pocket flap 18 secured thereto along the line of stitches at 17, with a button 19 secured thereto and to the panel section 13.

10 The outer garment portion 10 preferably also includes a pair of similar rear panel sections 20 and 21, which are joined to each other along a central vertical line of stitches 22.

The rear panel sections 20 and 21 are joined to the front panel sections 13 and 14 along lines of stitches 23 and 24. Extending from the line of stitches at 23 to the line of stitches at 24, and along the upper margins of the rear panel sections 20 and 21, gathered along their upper part, a piece of elastic webbing 25, or the like, is preferably provided to resiliently urge the upper part of the rear panel sections 20 and 21 to gathered condition thereby to aid in holding the garment in position on the child.

The outer garment 10, heretofore described, is substantially conventional, with a waist opening at 26 and leg openings at 27 and 28.

The front panel sections 13 and 14 at their lower central marginal portions have an inwardly disposed upwardly facing transverse tab 29 which is preferably provided with a relatively inelastic strip of tape 30 or the like to which separable fastener elements 31 are secured.

The rear panel sections 20 and 21 at their lower central marginal portions have an outwardly disposed downwardly facing transverse tab 32 which is provided with a relatively inelastic strip of tape 33 or the like to which separable fastener elements 34 complementary to and engageable with the fastener elements 31 are secured for permitting opening, and closing, of the crotch as desired.

40 The outer garment portion 10 has the inner garment portion 11 completely contained therein. The inner garment portion 11 preferably comprises a front panel section 35 and a rear panel section 36, connected to each other along one side margin by a line of stitches 37 and along the other side margin by a line of stitches 38.

45 The rear panel section 36, at the top thereof, is connected to the upper margins of the rear panel sections 20 and 21 with its upper edge interposed between the elastic webbing 25 and these upper margins so as to be simultaneously gathered with the gathering of the upper margins of the rear panel sections 20 and 21.

The front panel section 35, at the top thereof, is connected to the upper margins of the front panel sections 13 and 14 with its upper margin joined interiorly at the junction of the waist band portion 16 and the front panel sections 13 and 14 and held by the same line of stitches 17.

The lower front central margin 40 of the front panel section 35 is preferably less in width than the combined width of the marginal portions which make up the tab 29 (see Fig. 3) and is joined thereto along a line of stitches 41.

60 The lower rear central margin 42 of the rear panel section 36 is preferably less in width than the combined width of the marginal portions which make up the tab 32 (see Figs. 3 and 4), is joined thereto along a line of stitches 43 and extends thereover and then therebelow and between the tape 33 and the remainder of the tab 32 where it is secured by a line of stitches 44.

70 The lower margins of the sections 35 and 36, between the ends of the tabs 29 and 32 preferably have elastic cords 45 therealong and gathered or contracted so as to

provide for an initial contraction of the lower margins of the sections 35 and 36 with expansion or elongation, as required, to accommodate the leg of the child.

In use, and with the crotch either open or closed, the garment can be positioned on the child with the waist band portion 16 at the proper location. The crotch, if unfastened, can be closed by securing the fastening elements 31 and 34 together.

The lower margins of the front and rear panel sections 35 and 36, between the tabs 29 and 32 on each side will be held in snug engagement with the legs of the child by the elastic cords 45 while at the same time the outer garment will be disposed in its normal position and in an attractive manner.

If it is desired to use a diaper, the garment can be quickly and easily opened at the crotch and a diaper applied. The waterproof character of the interior garment portion 11 and the engagement of the lower margins thereof with the legs of the child will provide proper protection.

I claim:

An infant's garment comprising an outer garment portion having a front panel part with an upper marginal waist portion and side margins, a rear panel part with an upper marginal waist portion and side margins respectively connected to the side margins of the front panel

part, one of said waist portions having a contracted elastic band therealong, said front panel part having a lower central terminal crotch tab and said rear panel part having a lower central terminal crotch tab, members for releasably holding said crotch tabs in engagement to provide a closed crotch for the outer garment portion, a separate inner garment portion of waterproof material from its upper to its lower extremities interiorly disposed with respect to said outer garment portion and having a plurality of connected panel parts connected along their upper margins to the upper margins of the front and rear panel parts of the outer garment portion, said inner panel parts having lower margins secured to the crotch tabs and separable therewith, said inner garment portion having lower marginal parts connecting said tabs on each side, said inner garment portion being free from attachment to said outer garment portion at its other locations, and said last marginal parts each having a contracted elongatable member therealong.
